UNITED STATES PATENT OFFICE.

ZOTIQUE BEAUDRY, OF LYNN, ASSIGNOR OF TWELVE-SIXTEENTHS TO THOMAS L. HOITT AND UDGER BELIVEAU, BOTH OF SAME PLACE, JOHN E. PECK, OF NEWTON, MASS., AND HENRY L. BROWN, OF MIDDLETOWN, CONN.

HEEL-BURNISHER FOR BOOTS AND SHOES.

SPECIFICATION forming part of Letters Patent No. 240,947, dated May 3, 1881.

Application filed November 13, 1880. (Model.)

To all whom it may concern:

Be it known that I, ZOTIQUE BEAUDRY, of Lynn, in the county of Essex and State of Massachusetts, have invented certain new and 5 useful Improvements in Heel-Burnishers for Boots and Shoes, of which the following is a full, clear, and exact description.

This invention relates to a burnisher adapted more especially for hand use; and this improvement in boot and shoe heel burnishing tools consists, first, of a burnishing-face having its surface across its width shaped to fit substantially the surface of the edge of a boot or shoe heel across the thickness of the heel, 10 and in the direction of its length made convex, and at end of such convexity provided with a similar wing or extension, each of which wings or extensions is in continuation of said longitudinal convex portion, and has such a 15 general direction in relation to it that in the burnishing by the longitudinal convex portion of the burnisher-face of the periphery or edge of the boot or shoe heel at or near the line of juncture of such edge with the front edge of 20 the heel the burnisher-face will project in one direction therefrom and be in position to have a rest or bearing upon the edge of the heel beyond and in addition to its bearing by such convex portion, and will project in the other 25 and opposite direction therefrom, but in such projection be wholly clear and free from contact and of all liability of contact with the edge of the boot or shoe sole which is on the corresponding side of the boot or shoe as that 30 of the surface of the heel so being burnished; second, in the combination, with a burnishing-tool having a burnishing-face suitable for burnishing the edges of boot and shoe heels, of an edge or edges for operating and working 35 upon the heel-edge at or near the upper, to burnish and smooth and otherwise to prepare the surface of the heel at such place, which edge or edges are arranged and applied in relation to the main burnishing-face of the bur- 40 nisher to be projected or withdrawn therefrom, and thus put into and out of their plane of operation at pleasure, all substantially as hereinafter described; third, in the combination, 45 with a hand-burnisher for burnishing the edges of boot and shoe heels, of a rest or brace for the arm or body of the operator, through which the burnisher is handled and manipulated, all 50 substantially as hereinafter described.

In the accompanying plate of drawings my improvements in heel-burnishers for boots and 55 shoes are illustrated.

In Plate 1, Figure 1 is a side elevation. Fig. 2 is a plan view.

In Plate 2, Fig. 3 is a vertical section on line *x x*, Fig. 1, with the arm-rest and its connection with the burnisher in elevation back of the parts in section. Fig. 4 is a front elevation, with the edge or edges for working against the heel at or near the upper of the boot or shoe placed in their operating or working position in relation to the main burnishing-face of the burnisher; Fig. 5, a diagram illustrative of the position of the burnishing-face in its length when working at or near the juncture of the round edge or periphery and the 70 front edge of the heel.

In the drawings, A represents a burnisher-head. This burnisher-head is chambered, as at B, perforated, as at *a a*, and provided with a gas-pipe, C, which enters its chamber B, all 75 so that it can be heated by burning gas therein.

D is a flexible or india-rubber tube making the connection between the gas-pipe C and the gas-supply.

E is the burnishing-face of the burnisher-head. This face E, across its width, is of a convex shape, and corresponds in such convexity with the usual concave outline of the edge of boot or shoe heels in the direction of the thickness of the heel, or, in other words, between 80 the treading-face of the heel and the upper of the boot or shoe. This burnishing-face, in the direction of its length has a convex portion, *b*, the curve of which is of a short radius, and at each end of such convex portion there is a similar wing or extension, *c*. Owing to this construction of the burnisher-head, when the convex portion *b* is in operation on the heel of a boot or shoe, one of the extensions *c* thereof will have a bearing upon the outer edge of the 95 heel, and the other extension *c* of the convex portion *b* will project outward in such a position as to be entirely free from contact with that edge of the boot or shoe sole which is on the same side of the heel that is being operated 100 upon. This relative arrangement and direction of the wings *c* and convex portion *b* of the burnishing-face and their position when burnishing the heel at or near each of its corners with the front of the heel are plainly illustrated in Fig. 5 of the drawings, in which F rep-

resents the contour of a boot or shoe sole and heel; *d*, the corner or juncture of the round edge *f* and front edge, *g*, of the heel; *h*, the edge of the sole; *b*, the convex face of the burnisher, and *c c* the wings or extensions thereof at each end of such convex face.

- This peculiar formation of the burnisher-face in the direction of its length possesses several advantages—as, for instance, some portion of such face is always overlapping the edge of the heel beyond the part working and operating thereof, that all possibility or danger of the face leaving the edge of the heel at its corner or juncture with the front edge of the heel is avoided, and that there is no possibility of injuring the edge of the sole of the boot or shoe while burnishing the outer edge of the heel at or near either of its corners or junctures *d* with the front edge of the heel.
- 20 The wings or extensions, along their length, may be either straight or curved, and it is preferable to have them curved, but each with a curve of long radius. They are so shown in the drawings.
- 25 The burnishing-face at one side has a rigidly-attached flange, *G*, which rests against the treading-face of the heel as the burnishing-face is manipulated to burnish the outer edge of the heel, and at the other and opposite side it has an edge, *H*, in two parts, both of which along their length have the same general shape and direction as the burnisher-face *E*. One part, *l*, of this edge *H* and the burnishing-face are corrugated across their width, as shown, and as common in heel-burnishers, and the other part, *m*, is smooth. This double edge *H* is for "beading," as it is termed, the heel at and near the upper, and the two parts *l m* of the double edge *H* are in one piece with a stock, *J*.
- 30 This stock *J* is attached to a rod, *K*, which plays through a socket-arm, *n*, fastened to the burnisher-head, and the said rod *K*, at the end opposite to that which carries the stock *J*, projects from the socket *n*, and its projecting portion is surrounded by a coiled spring, *o*, which is confined between the end of the socket and a collar, *L*, which is secured, by a set-screw, *p*, to the rod *K*, and has a thumb-piece, *M*, that projects at right angles therefrom and
- 35 lies between the socket and the burnisher-handle *N*. By pressing upon the thumb-piece with the thumb of the hand which grasps the handle *N*, its double edge *H* to the stock *J* is made to project beyond the burnishing-face, and thus is placed in position for work. This movement of the double edge *H* to project it from the burnisher-face is against the coiled spring *o*, so that, on releasing the pressure through the thumb-piece *M* on such spring, obviously the spring will, in reacting, automatically retract and place such double edge *H* inside the plane of the burnishing-face, and thus out of the plane of work upon the outer edge of the heel.
- 40 65 *O* is an arm lying alongside of and parallel to the rod *K*, which carries the double edge *H*, as described. This arm *O* is secured to a col-

lar, *q*, of such rod, and this collar, as shown, is between the thumb-piece collar *L* and the spring *o*; but the arm *O* may, if desired, be attached directly to the thumb-piece collar.

In pressing the double edge *H* to project it from the burnishing-face *E* the extent of such projection is limited by the abutment of this arm against the end of the socket *n*, through which the rod carrying the double edge *H* plays, and thus obviously, by adjusting this arm *O* upon the said rod, the extent of the projection of the beading and smoothing edges *l m* beyond the burnishing-face *E* may be regulated as desired, and this adjustment of the arm *O* is secured by adjusting the thumb-piece collar.

The handle *N* of the burnisher-head may be of any suitable shape to be grasped by the hand; but it is preferable to give it the form and construction shown and described in another application for Letters Patent of the United States filed by me June 26, 1880, for improvements in hand-burnishing tools, and as such shape is fully and in detail described therein, and as it constitutes no part whatever of the present invention, it is not deemed necessary to herein again repeat it.

P is a rest suitably shaped to surround the front and sides of a person's arm between the shoulder and the elbow. This rest *P* is swiveled to the end of a rod, *Q*, and at each end of such swivel the rest *P* is connected by coiled springs to a cross-arm of such rod *Q*.

The arm-rest *P* swivels or turns against these springs, and they, by their reaction, return the rest to its normal position in relation to its carrying-rod *Q* on release of the force or pressure by which the rest turns or swivels. This arm-rest-carrying rod extends to and swivels and turns within a socket which is at the upper end of and in line with the burnisher-handle *N*, and between such handle and arm-rest the said rod is of such length and curvature that with the handle grasped by the hand the arm-rest will be against and about the front and sides of the arm, between the shoulder and elbow, and thus act as a means of bracing the burnisher in its work, all as is plainly to be seen by an inspection of Fig. 1 of the drawings.

The rest-carrying rod *Q*, at each side, is connected by spiral springs *S* to the burnisher-handle, this connection, as shown, being made through a collar, *s*, attached by set-screw *t* to the socket *T*, in which such rod swivels, and thus the turn or swivel of the burnisher-handle upon the arm-rest-carrying rod, or of such rod *Q* upon the burnisher-handle, is in either and both cases and in either and both directions of such swing against the springs *S S*, which on reacting serve to return the parts to their normal position.

The burnishing implement herein described by preference is to be suspended by spiral springs or other suitable elastic and flexible connections from a suitable support, and when used its handle *N* is grasped by the hand, with the thumb of such hand placed over the thumb-

piece M, and with the arm of the same hand, between the elbow and the shoulder, within and at rest against the arm-rest P. The tool thus being held by the operator, the flange G 5 of the burnisher-head is placed against the treading-face of the heel, and then the burnishing-face E presented to and rolled and rocked or otherwise moved against the outer edge of the boot or shoe heel, while at the 10 same time the outer edge of the heel is rolled about the burnisher-face, but in an opposite direction to the roll of the burnishing-face about it. By this roll of the burnishing-face and of the outer edge of the boot or shoe heel 15 the outer edge of the heel is burnished as desired and polished with but few movements of the burnisher and but little time. After the outer edge of the heel is burnished the double edge H is then brought into play by 20 pressing downwardly upon the thumb-piece, so as to produce from it the corrugations and smoothing off the heel at or near its connection with the upper of the boot or shoe, and this is accomplished when the double edge is 25 so brought into play by rolling or otherwise passing the double edge about the heel and the heel about the double edge.

The arm-rest P, with its brace-rod connecting it to the burnisher-head, obviously enables 30 the operator to hold the tool with greater firmness and steadiness to its work, and as the arm-rest is swiveled to the brace-rod Q and the brace-rod to the burnisher-head, plainly the tool and brace-rod can be moved in all directions necessary, thus giving the utmost freedom and ease to the manipulations of the tool, while at the same time the burnisher is given 35 a support and brace directly from the operator's arm in addition to the support and brace 40 from the hand of the operator which is grasping the burnisher-handle.

It is obvious that an arm-rest connected by a brace-rod, Q, to a hand heel-burnisher, as herein described, is as applicable to other hand-burnishers as to the one herein particularly 45 shown and described.

The double edge H, for beading, corrugating, and smoothing the outer edge of the heel near the upper, obviously may be arranged for 50 a separate operation of each edge in lieu of the combined operation herein described, and again, obviously, the arrangement of it herein described, for placing it in and out of operating position, is applicable to other forms of 55 heel-burnishers as well as the one herein particularly described.

The burnisher-head may be adapted to be heated in other ways than by gas, as described— 60 as, for instance, it may be made solid and heated from time to time by placing it in a suitable furnace; but it is preferable to heat it by gas conveyed through a flexible connection with the gas-supply, as it thus is always under heat, and no time is lost to reheat it, as would 65 be the case if adapted to be heated in a furnace.

As shown and particularly described, the brace-rod Q, leading from the arm to the hand burnishing-tool, and also the arm-rest P, are swiveled to each other and the brace-rod to 70 the tool, and while, for obvious reasons, this connection of them is preferable, yet either or both of such connections may be rigid, if so desired.

While the brace-rod Q has been herein particularly described as adapted to rest against the arm of the operator, it is obvious that the same results and benefits would be obtained by resting it against the body of the operator. 75

Having thus described my invention, what 80 I claim, and desire to secure by Letters Patent, is—

1. A heel-burnisher for boots and shoes, the working-face of which is constructed of the convex portion b and the two wings or extensions c c, forming opposite continuations of the convex portion, all substantially as shown, and for the purpose described. 85

2. The combination, with a heel-burnisher for boots and shoes, of a suitable block or support provided with two edges, l and m, capable of adjustment in relation to the burnisher substantially as shown and described. 90

3. The combination, with a boot and shoe burnishing tool connected with a vertically-arranged brace-rod connected with the burnishing-tool, and extending in an upward and outward direction from the same, the upper end of said brace-rod being provided with a rest arranged to bear against the arm of the operator above the elbow, substantially as described, whereby force from the arm can be applied to the burnisher, as set forth. 95

4. The combination, with a burnisher for boots and shoes, of a brace-rod having at one end a swiveled connection with the burnisher and at the other end provided with a swiveled rest adapted to bear against the arm above the elbow, substantially as described, for the purposes set forth. 105

5. In a hand-burnisher for boots and shoes, a stock, J, provided with the edge or edges l m, located at one side of a suitable burnishing-face for the heels of boots and shoes, in combination with the rod k, socket n, thumb-piece M, and spiral spring r, all arranged together substantially as and for the purpose described. 115

6. In a hand-burnisher for boots and shoes, the combination, with the burnisher, of a brace-rod, Q, which is swiveled thereto and to an arm-rest, P, and at each side is provided with spiral springs or other suitable elastic connections, all substantially as and for the purpose described. 120

In testimony whereof I have hereunto set 125 my hand in the presence of two subscribing witnesses.

ZOTIQUE BEAUDRY.
